(57) **CLAIM**

The ornamental design for a bench seat, as shown and described.

DESCRIPTION

FIG. 1 is a front perspective view showing our new design of a bench seat for use in an aircraft;

FIG. 2 is a rear perspective view of the bench seat of FIG. 1;

FIG. 3 is a front view of the bench seat of FIG. 1;

FIG. 4 is a rear view of the bench seat of FIG. 1;

FIG. 5 is a right side view of the bench seat of FIG. 1;

FIG. 6 is a left side view of the bench seat of FIG. 1; and,

FIG. 7 is a top view of the bench seat of FIG. 1.

The broken lines represent environmental structure and portions of the bench seat which form no part of the claimed design.

1 Claim, 7 Drawing Sheets
